[57] **CLAIM**

The ornamental design for an infrared electronic sensor for the detection of heat, as shown and described.

DESCRIPTION

FIG. 1 is a top, front and side perspective view of an infrared electronic sensor for the detection of heat, showing my new design;

FIG. 2 is a front elevational view thereof;

FIG. 3 is a side elevational view thereof from the right of FIG. 2, the side elevational view opposite that shown in FIG. 3 being the mirror image thereof;

FIG. 4 is a rear elevational view thereof;

FIG. 5 is a top plan view thereof; and,

FIG. 6 is a bottom plan view thereof.
